UNITED STATES PATENT OFFICE

113,262

DESIGN FOR A TAP KNOB

Francis C. Fisher, Syracuse, N. Y.

Application August 11, 1938, Serial No. 79,276

Term of patent 14 years

To all whom it may concern:

Be it known that I, Francis C. Fisher, a citizen of the United States, residing at Syracuse, in the county of Onondaga and State of New York, have invented a new, original, and ornamental Design for a Tap Knob, of which the following is a specification, reference being had to the accompanying drawing, forming part thereof.

Figure 1 is a front elevational view of a tap knob showing my new design.

Figure 2 is a side elevational view thereof.

Figure 3 is a top plan view thereof.

The design consists in a tap knob in which the

generally rounded head portion is provided at one side with a flattened sign area facing upwardly at an inclined angle and also provided at diametrically opposite sides of the head portion with smaller circular sign areas which conform to the surface contour of the knob, the neck portion of the knob being of gradually tapering form having substantially straight walls which merge with the rounded head portion, all as shown.

I claim:—

The ornamental design for a tap knob, as shown and described.

FRANCIS C. FISHER.
